(57) **CLAIM**

The ornamental design for a bug-out pet dish, as shown and described.

DESCRIPTION

FIG. 1 is a front, top and left side isometric view of a bug-out pet dish showing my new design;

FIG. 2 is a front elevational view thereof, all other elevational views being the same;

FIG. 3 is a top plan view thereof; and,

FIG. 4 is a bottom plan view thereof.
